REFRIGERATING APPARATUS

Charles F. Henney, Dayton, Ohio, assignor to
General Motors Corporation, Dayton, Ohio, a
corporation of Delaware

Application October 9, 1935, Serial No. 44,249

5 Claims. (Cl. 62—6)

This invention relates to refrigeration.

It is among the objects of this invention to provide a method of, and apparatus for, conditioning air, in which the various functions of the psychrometric conditions of air are properly maintained.

Further objects and advantages of the present invention will be apparent from the following description, reference being had to the accompanying drawing, wherein a preferred form of the present invention is clearly shown.

In the drawing:

Fig. 1 is a diagrammatic representation of an apparatus embodying features of my invention;

Fig. 2 is a wiring diagram applicable to the apparatus shown in Fig. 1;

Fig. 3 is a wiring diagram of a manual control for the air blower; and

Fig. 4 is a modified wiring diagram applicable to the apparatus shown in Fig. 1.

In practicing my invention, refrigerant is evaporated in an evaporating zone and the gaseous refrigerant is preferably withdrawn therefrom at a substantially constant volumetric rate. Air is forced in thermal exchange with the evaporating refrigerant in the evaporating zone, and the velocity of the air is changed to compensate for varying psychrometric conditions in the air.

An apparatus suitable for accomplishing this is shown in Fig. 1. In this apparatus, an evaporating zone is maintained in the evaporator 10. Evaporated refrigerant is withdrawn from this evaporator at a substantially constant volumetric rate by means of a compressor 11 driven by a constant speed electric motor 12. The compressed refrigerant is discharged from the compressor into the condenser 13, from whence the liquefied refrigerant flows through the pipe 14 to the evaporator 10. In passing to the evaporator 10, the refrigerant flows through an automatic expansion valve 15, which is of the type which automatically discharges liquid refrigerant to the evaporator when the pressure thereof is reduced below a predetermined limit. This valve is also automatically throttled by a thermostatic bulb 16, placed at the outlet of the evaporator so that when the refrigerating effect reaches the bulb 16, the flow of liquid refrigerant is automatically throttled at the valve 15.

The condenser 13 may be of any usual construction. For example, as diagrammatically shown, it may be a cylindrical casing in which a water coil 17 is placed. Flow of water through the coil 17 may be controlled by a pressure re-

sponsive valve 11a, responsive to the head pressure of the compressor.

Air is forced in thermal exchange with the evaporating zone or evaporator 10 by any suitable means, such as a fan or blower 18. This blower is driven by suitable means capable of varying the speed thereof. Thus it may be driven by an electric motor 19 of the variable speed type. Air from the room 20, or from outside the room 20, or both, may enter through the inlets 21 and 22, and flows past the evaporator 10 and is discharged through the outlet 23 into the room 20.

The operations of the compressor 11 and the blower 18 are controlled in accordance with functions of the psychrometric conditions of air. A way of accomplishing this is diagrammatically indicated in Fig. 2. Preferably the operation of the compressor 11 is controlled so that it operates whenever the temperature conditions or the relative humidity conditions in the room 20 require it. The blower 18 is operated at varying speeds as the relative humidity of the air in the room 20 varies when the temperature in the room is sufficiently low so that the highest speed of air is not necessarily required.

The thermostat 24, which may be either a dry bulb or a wet bulb thermostat, is placed in a position to be responsive to temperature conditions inside the room 20, it being understood, however, that it may be placed outside of the room if desired. Whenever the temperature in the room 20 is above a predetermined limit, such as to require the highest blower speed, the contact 25 closes upon the contact 26. This energizes the solenoid 27 and opens the contacts 28. As will be hereinafter more apparent, the opening of the contacts 28 prevents the blower motor 19 from running at a slow speed. In this manner the flow of air past the evaporator zone 10 is at its maximum whenever the temperature conditions in the room 20 are relatively high and above a predetermined limit. When the temperature falls to, or below, another predetermined limit, the contact 25 closes upon the contact 29 and opens contact 26. This energizes the solenoid 30 and closes the contacts 31, thus placing the solenoid 32 under the control of the humidostat contact 34. At the same time the contacts 33 are opened and contacts 28 are closed, thus making it possible for the humidostat to vary the blower motor speed.

The relative humidity in the room 20 (or outside the room 20, depending on the position of the humidostat H inside or outside the room) 55

determines the speed of the blower 18 and the operation of the compressor 11 when the temperature conditions are below the last named predetermined minimum. If the relative humidity conditions are below a predetermined degree, the contact 34, under the control of humidostat H, closes upon the contact 35, and when the relative humidity conditions are above a predetermined degree the contact 34 closes upon the contact 36. Thus when the relative humidity conditions are relatively low so that the contacts 34 and 35 are closed, and when at the same time the temperature is relatively low so that contacts 25 and 29 are closed, the compressor motor 12 is stopped since refrigeration is not required. This is accomplished because current flows to the solenoid 32 which in turn opens the contacts 50. This opens the electric circuit to the motor 12 and stops the compressor. When the relative humidity rises, but the temperature remains sufficiently low to keep the contacts 25 and 29 closed, then the contacts 34, 35 are opened and the contacts 34, 36 closed. The opening of the contacts 34, 35 de-energizes the solenoid 32, thus closing the contacts 50 and causing the compressor motor 12 to operate. The closing of the contacts 34, 36 causes current to pass through the contacts 28, through the resistance 37 and the main winding 38 of the motor 19. This causes the motor 19 to operate at its slow speed thus causing air to be forced over the zone 10 at a relatively slow speed.

When the relative humidity is relatively high, so that the contacts 34, 36 are closed, and if the temperature is also high at this time, so that the contacts 25, 26 are closed, then the solenoid 27 is energized and closes the contacts 39. This shunts the resistance 37 and places the main winding 38 across the lines 40, and causes the blower motor 19 to operate at full speed.

The motor 19 may be of any suitable self-starting type such as an induction-repulsion start motor or a shaded pole motor. The actions of the contacts 25 and 34 are preferably snap acting.

The change from high speed to low speed of the motor 19 may be manually controlled, if desired. This may be accomplished as indicated in Fig. 3. One of the power lines 40a may be connected to the central post 41 of the manual switch 42. The post 1 may be connected to one side of the main winding 43 of a motor corresponding to motor 19. The post 2 may be connected to an intermediate point of the resistance 44 while the point 3 is connected to place the entire resistance 44 in the circuit. The manual switch 42 is of the character which can be rotated only clockwise and is so arranged that the contact arm 45 snaps from the positions 1, 2, 3, 4 and back to 1 only in a clockwise direction. The position 4 is an open position so that the motor 19 is stopped at this position. When the contact is moved to position 1, current flows through the main winding 43. At this time a starting control, such as a centrifugal control, maintains the contact 46 against the contact 47. This places the starting winding 48 also across the lines and brings the motor up to speed. When sufficient speed has been attained the contact 46 snaps down to the contact 49. If the contact arm 41 remains in position 1, the motor continues to operate at full speed. If the contact 45 is snapped to position 2, then a portion of the resistance 44 is placed in series with the winding 43 and the motor is operated at a slower speed. If the contact 45 is then snapped to the position

3 the entire resistance 44 is placed in series with the winding 43 and the motor 19 operates at still a slower speed. Thus the flow of air over the evaporator 10 may be manually controlled by means of the switch 42 to produce any number 5 of different air velocities over the evaporating zone.

By the arrangement shown in the drawing, refrigerant is withdrawn from the evaporating zone 10 at a substantially constant volumetric 10 rate by means of the constant speed compressor 11. Air is forced over the evaporator 10 by means of the fan 18, and the velocity of the air is regulated in accordance with air conditions either automatically by the humidostat H or 15 manually by means of the switch 42. When air flows over the evaporator at the slower rate, a larger amount of moisture is removed from the air in comparison to the reduction of the dry bulb temperature. This produces a relatively 20 large amount of dehumidification in comparison with the reduction in sensible temperature.

It may also be desirable to reduce the speed of the compressor when the temperature is low and the relative humidity is high. This may be 25 accomplished as shown in Fig. 4 which shows how the wiring of Fig. 2 may be modified. The switch bar 60 under the control of solenoid 27 may be provided with contact 51 which bridges the contact 62 in the compressor motor line. 30 When the temperature is low and the bar 60 is down, then the resistance 63 is placed in series with the motor 12 and causes the compressor to operate at reduced speed. This causes the air velocity and the refrigerating capacity to be reduced simultaneously when the temperature is low and the relative humidity is high. The reduced air velocity and reduced refrigeration capacity are so calibrated that moisture is removed from the air, but the reduction in sensible 40 temperature is small compared with the heat infiltration into the room and the addition of heat by its occupants.

While the form of embodiment of the invention as herein disclosed, constitutes a preferred 45 form, it is to be understood that other forms might be adopted, all coming within the scope of the claims which follow.

What is claimed is as follows:

1. An air conditioning apparatus comprising, 50 a compressor, condenser and evaporator in refrigerant flow relationship, a blower for blowing air over said evaporator, means for automatically varying the operation of said blower in accordance with relative humidity conditions, and 55 means for operating said compressor at either a high speed, low speed or for stopping said compressor in accordance with a function of the psychrometric conditions of air.

2. The method of conditioning air which comprises withdrawing evaporated refrigerant from an evaporating zone into a liquefying zone, circulating air to be conditioned in thermal exchange with said evaporating zone, withdrawing said refrigerant slowly and circulating said air 60 slowly when the humidity is high and the temperature is low, withdrawing said refrigerant rapidly and circulating said air slowly when both the humidity and temperature are high, and withdrawing said refrigerant rapidly and 65 circulating said air rapidly when the humidity is low and the temperature is high.

3. The method of conditioning air which comprises withdrawing evaporated refrigerant from an evaporating zone into a liquefying zone, cir- 70

culating air to be conditioned in thermal exchange with said evaporating zone, withdrawing said refrigerant slowly and circulating said air slowly when the humidity is high and the temperature is low, withdrawing said refrigerant rapidly and circulating said air slowly when both the humidity and temperature are high, withdrawing said refrigerant rapidly and circulating said air rapidly when the humidity is low and the temperature is high, and stopping both the flow of refrigerant and the circulation of air when both the temperature and humidity are low.

4. In combination, a compressor, condenser and evaporator in refrigerant flow relationship, blower means for circulating air in thermal exchange with said evaporator, means for operating said compressor and said blower slowly when the humidity is high and the temperature is low,

means whereby said compressor operates rapidly and said blower operates slowly when the humidity and the temperature are both high, and means whereby said compressor and said blower both operate rapidly when the humidity is low 5 and the temperature is high.

5. Air conditioning apparatus comprising, a compressor, a condenser and an evaporator in refrigerant flow relationship, a blower for blowing air over said evaporator, means responsive 10 to changes in the moisture content of the air for automatically varying the operation of said blower, and means for operating said compressor at either a high speed, low speed or for stopping said compressor in response to changes in at 15 least one function of the psychrometric condition of the air.

CHARLES F. HENNEY.
